UNITED STATES PATENT OFFICE.

ALFRED H. SMITH, OF NEW YORK, N. Y.

COMPARTMENT FREIGHT CAR.

1,407,594.

Specification of Letters Patent. Patented Feb. 21, 1922.

Application filed June 9, 1920. Serial No. 387,519.

To all whom it may concern:

Be it known that I, ALFRED H. SMITH, a citizen of the United States, residing at New York city, State of New York, have 5 invented certain new and useful Improvements in Compartment Freight Cars, of which the following is a specification.

In another application filed June 9, 1920, Serial No. 387,517, I have described a new 10 system of freight transportation involving a series of independent freight compartments placed upon a single car and it is the object of this invention to provide means whereby such compartments may be securely 15 locked on the car, and with this and other objects in view my invention consists of the parts and combination of parts, as will be hereinafter set forth.

In the drawings:

20 Figure 1 is a detail end elevation of a freight compartment on a car showing a locking means between the car and compartment.

Figure 2 is a side elevation of two compartments mounted on a car and locked thereon with the locking means shown in 25 Figure 1.

Figure 3 is a top plan view of Figure 2, the compartments being in section.

30 Figure 4 is a detail vertical sectional view on the line 4-4 Figure 3.

The reference number 1 designates a freight holding compartment, broken away. The construction of this compartment may 35 be of any approved form. At the four bottom corners of each compartment I provide a locking attachment which I will now describe.

One member of the locking attachment 40 comprises a casting 2 which is suitably secured to a wall of the compartment by means of rivets 3. A lug 4 extends forwardly from the casting and beyond the end wall of the compartment and is provided with an 45 elongated slot 5, said slot extending vertically. A closed link 6 is loosely mounted in the slot 5, said link being preferably elongated as shown in the drawing whereby it has an extended bearing in the slot 5 of the lug 4, the lug being comparatively wide.

The casting 2 is a right angle casting and fits around the corner of the compartment 1 as shown in the drawing and is provided with a depending foot 7 which functions 55 to elevate the floor of the compartment above the surface upon which the compartment

rests, the foot 7 being reinforced by means of the Z bar 8.

A rectangular hollow post 9 is secured at its lower end by means of rivets 11 to the side sills 12 of the car while the upper ends of the posts project a suitable distance above the floor of the car and are provided with inwardly extending lugs 13 which project over and rest upon the car floor and which are secured by means of bolts.

The inner faces of the lugs 13 are downwardly and inwardly inclined as at 14 which constitute wedging faces which are adapted to be engaged between the wedging 70 faces 15 depending from an arm 16 of the casting 2. The extreme lower end of the arm 16 is bent rearwardly on the floor line of the car and forms with the foot 7 and the Z bar 8 an extended bearing for the compartment when placed upon a supporting surface whereby the floor of the compartment is elevated above any water that may accumulate on the surface upon which the compartment may be placed.

The post 9 is provided, near its upper end, with an opening 17 through which a locking pin 18 is adapted to pass and be positioned above the loop 6 when the loop is thrown over the post as shown in the drawing whereby the loop is prevented from becoming accidentally disengaged from the post. To prevent the loss of the pin 18 I secure it by means of a chain 19 which chain is anchored to a suitable support such for instance as one of the bolts.

In the present invention in order to prevent the link 6 from becoming distorted when in unlocked position when the compartment is loaded and on a supporting surface I provide the elongated slot 5 whereby the link is free to move upwardly in said slot and the upper end of the slot is so positioned relative to the supporting feet of the compartment that the lower end of the link 100 is free to move upwardly beyond the plane of the supporting surface.

Changes may be made in the details of the construction without departing from the scope of the claims.

What I claim is:

1. The combination with a freight car, of a series of independent freight compartments mounted on said car, a casting secured to the side sills of the car and terminating above the car floor, a lug integral with said casting and extending over the car floor and

having a downwardly and inwardly inclined face constituting a wedging element, and a casting attached to the lower corner of the compartment having a downwardly and inwardly inclined face adapted to coact with the said inclined face of the casting on the car, and means locking the compartment to the said casting on the car.

2. The combination with a car, of a series 10 of independent freight compartments detachably mounted on the car, members secured to the lower corners of each compartment and projecting below the floor of the compartment and having an under bevelled 15 face, a loop pivotally secured to said member, a stake secured to the side sills of the car and projecting above the floor of the car, a bevelled lug extending inwardly from said stake on the car floor, said bevelled 20 faces adapted to engage each other when the compartment is on the car; said loop being adapted to engage said stake and means on the stake to lock the loop to the stake.

3. The combination with a freight car, of 25 a freight compartment detachably mounted on the car, a foot secured at each lower cor-

ner of the compartment, and projecting below the floor of the compartment, a loop pivotally and vertically slidably mounted on said foot whereby the loop may move vertically and not be subjected to the load of the compartment when the compartment is supported on its feet.

4. The combination with a freight car, of 30 a freight compartment detachably mounted on the car, of a stake secured to the side of the car and projecting above the floor of the car, a loop loosely connected to the compartment and adapted to engage said stake to anchor the compartment to the car.

5. The combination with a freight car, of 35 a series of independently detachable compartments on said car, a series of stakes secured to the side of the car and projecting above the floor of the car, a series of loops 40 mounted on the lower corners of the compartments to swing and move bodily vertically and adapted to engage the stakes to anchor the compartments to the car, and means to lock the loops to the stakes.

In testimony whereof I affix my signature. 45
ALFRED H. SMITH.
